UNITED STATES PATENT OFFICE.

GERALD W. HART, OF WEST HARTFORD, CONNECTICUT, ASSIGNOR TO THE HART & HEGEMAN MANUFACTURING COMPANY, OF HARTFORD, CONNECTICUT.

DESIGN FOR AN ELECTRIC-SWITCH BASE.

SPECIFICATION forming part of Design No. 26,651, dated February 16, 1897.

Original application filed September 28, 1896, Serial No. 607,266. Divided and this application filed January 25, 1897. Serial No. 620,695. Term of patent 14 years.

To all whom it may concern:

Be it known that I, GERALD W. HART, a citizen of the United States, residing at West Hartford, county of Hartford, and State of Connecticut, have invented and produced a new and original Design for Electric-Switch Bases, of which the following is a specification, reference being had to the accompanying drawing.

- 10 o The figure of the drawing is a perspective view of a switch-base, showing my design.
- 15 The leading or principal feature of my design is a configuration of a substantially circular cup-like shape having vertical grooves extending from the top to the bottom of the walls of the cup, open throughout their lengths and also open at top and bottom.
- 20 A is the wall of the cup-like base.
- 25 B is the bottom.
- 30 o C is the central space within the cup-like

base, and D D are the grooves extending from one end to the other of the wall A. These grooves extend from the top to the bottom, so as to be open at both ends as well as throughout their lengths. Such a base thus presents 25 to the eye a substantially circular cup-like body and also a cup-like body having grooves extending from top to bottom of the wall of the cup, each open at both ends and throughout its length.

35 This application is a division of a prior application, Serial No. 607,266, filed September 28, 1896.

What I claim is—

The design for a switch-base, substantially 35 as described and shown.

GERALD W. HART.
